United States Patent Office

Des. 183,381

Patented Aug. 19, 1958

183,381

SPOON OR SIMILAR ARTICLE

Theodore E. Cayer, Taunton, Mass., assignor to Reed and Barton Corporation, Taunton, Mass., a corporation of Massachusetts

Application October 14, 1957, Serial No. 48,081

Term of patent 14 years

(Cl. D54—12)

Fig. 1 is a front elevational view of a spoon embodying my new design;

Fig. 2 is a side elevational view of said spoon;

Fig. 3 is a rear elevational view of said spoon;

Fig. 4 is a cross-sectional view taken on line 4—4 of Fig. 1;

Fig. 5 is a cross-sectional view taken on line 5—5 of Fig. 1;

Fig. 6 is a cross-sectional view taken on line 6—6 of Fig. 1, and

Fig. 7 is a cross-sectional view taken on line 7—7 of Fig. 1.

I claim:

The ornamental design for a spoon or similar article, as shown.
